LOOSE LEAF BINDER

Application filed October 15, 1931. Serial No. 568,967.

This invention relates to improvements in loose leaf binders, particularly of the ring type. In the prior art, it is quite old to provide means so that the rings will not distort the side covers of a ring binder. My invention consists in an improved method for making the binder having means to protect the side covers and in a binder of improved construction.

10 The principal objective for putting the invention into use is in making improved ring binders, having very flexible side covers. When, for example, the covers are of fine appearing leather, of single ply and quite thin, 15 so as to be very flexible, the main problem of the invention is to protect such covers against taking permanently distorting impressions from the rings and to do this as neatly and invisibly as possible. Unless this is accomplished the binder will either have its covers distorted by the rings or its appearance changed by the additional parts to protect them. In the higher grades of flexible cover binders anything which requires a change in 20 appearance or visible construction is a serious matter. What is wanted is the simplest combination with the neatest appearance.

25 The best embodiment of the invention and its method of construction are fully disclosed in the accompanying drawings and following description.

Fig. 1 is a plan view of a well known commercial form of ring binder, in wide open position, with one cover partially cut away to permit a larger scale. This view does not show the invention in the structure, as one object of the invention is to retain the appearance of such a binder as it was before the new constructional feature is added;

40 Fig. 2 is a section through a cover on the line 2—2 of Fig. 1, indicating the relation of the cover, pressure distributing strip, and the hinged edge of the cover;

45 Fig. 3 is a plan view of one cover part before association with any metal part of the binder;

Fig. 4 is a section on line 4—4 of Fig. 3;

50 Fig. 5 is a view showing a part of the top inner portion of the cover part of Fig. 3 laid

back and how the metal parts are assembled on the corresponding lower portion;

Fig. 6 is a cross-section on line 6—6 of Fig. 5;

Fig. 7 is a view like Fig. 5 but showing a modified form of metal part in the form of a thin plate for the cover protector;

Fig. 8 shows another modification in which wires and plate are combined; and

Fig. 9 is a front view of the binder with its flexible covers pressed in by the hand, showing how such covers may be pressed against the binder rings in use and indicating the regions of pressure distribution and flexibility desired in a ring binder according to the invention in its best form.

The form of loose leaf book or binder illustrated, except for the details to be fully described below, is such a widely used commercial article that no full description of the metal parts associated with the back to hold and manipulate the rings 1 is necessary. It should, however, be understood in the illustration that the covers 2 and 3 are of the very flexible type, for example of single ply thin leather. The covers are hinged to the back along a line parallel and close to the sides of the ring plate 4. In the illustrated form the hinge part 5 on each cover is made of a strip of metal which is punched out, bent into ⁷⁰ U-form so as to make a narrow hinge plate of skeleton shape embracing the leather cover edge, and fastened to it by spaced claws 6 entering the leather from each side and in staggered spaced relation in respect to claws ⁷⁵ 85 on opposite sides. The scalloped U openings on the outer edge of the plate extend transversely to admit eyes in each opening, from a metal part or plate fastened to the rigid back of the book, see Fig. 2. A single pintle ⁸⁰ extends through all these eyes and lies at the bottom of the U-bend in hinge part 5. One desirable characteristic of such a hinge is that the metal parts do extend only a short distance transversely of the hinge line toward ⁹⁰ the outer edge of the book. They are fastened onto a very narrow edge of the cover part, so as to retain the flexibility of the cover right down to its hinge line. This is so desirable that in some flexible ring binders, the ⁹⁵ 100

hinge line is made by a crease in the leather alone, and the advantages of a metal hinge are discarded because in the ordinary hinge, the outer plate needs to extend too far over the cover part and flexibility in the cover near the hinge line is lost. The particular metal hinge here indicated has been more fully described in issued patents. It is important here merely to emphasize the desirability of a cover flexibility at the hinge line so that the cover will start to flex substantially at the hinge line and be flexible all the way out to its side edge. This is not a necessary feature of the present invention but it has a relation to the most desirable structural combination as will be pointed out. It is enough here to emphasize that it is desirable to avoid rigidity immediately adjacent the hinge line in the flexible cover binders. The type of metal hinge I show does avoid it, about as well as if the hinge line were made by scoring the leather between the back and cover. And furthermore, the hinge action itself is much better with the metal construction.

In Figs. 3 and 4 I show the cover before attachment to the hinge or associated with any metal parts. This is a piece of leather, thin enough to be flexible, of a single ply, usually with its grain on the outer side and a nice smooth finish to the leather on the inner side. According to my method, I partially split this cover between its outer and inner surfaces, as indicated at the left in Fig. 4. The leather splitting knife cuts in from the hinge edge to form two integral leaves or laminations 7 and 8 which merge integrally at 9 into the single ply of the cover stock and at a line spaced from the hinge edge and preferably less than the diameter of the rings. It is of distinct advantage to have the inner lamination 7, that is—the one with the inner surface of the cover on it, of less thickness than the outer one. The reason for this will appear.

The inner lamination 7 is turned back, and according to the preferred construction, a series of spring steel wires 10 are placed on the inner face of the outer lamination 8 and along that zone or region *a*, *b*, *c*, *d*, of the cover (see Fig. 3), between its top and bottom edges, where it is particularly desired to distribute the pressure exerted between the cover and rings as the book is used. These spring wires 10 are flexible and resilient, as in hatpin wire, for example. I prefer to space them in parallel position about as indicated. This will increase the transverse flexibility of the cover stock between them, at the region *a*, *b*, *c*, *d*. When the wires are placed in position, the inner lamination 7 is brought down over them. The two laminations 7 and 8 may then be cemented together with the wires between, in which case cement may be used over the whole contacting surface. But if desired, the end tabs 11 at top

and bottom only may be cemented, or just the cut edges may be cemented to obliterate the cut, particularly at the top and bottom edges where the appearance is important. The longitudinal edges of the cut, apart from the tabs, will be stapled together in any event by the claws 6 of the metal hinge construction.

After the wires have been placed between the laminations, it is desirable, particularly in very thin covers, to rest the outer face of the cover on a perfectly flat surface and press the laminations 7 and 8 together with the wires 10, for tight contact, as by a rubber pressure block, or a rubber hammer. Then if there is any tendency for the wires 10 to push up either surface of the cover, they will push up the inner surface, because the inner lamination was made thinner (see Fig. 4) than the outer one and the latter is supported by a flat surface in the joining operation. The wires 10 may be made so small in section and being preferably spaced apart, that their impression will not show, but if the larger wires are used they may be of a size such that where their form is discernible at all on the outside surface of the cover stock it will appear as if the leather had been very slightly scored to increase its flexibility near the hinge and not as if anything had been buried in the cover. And as an actual fact, with the wires spaced apart, the ordinary longitudinal flexibility of the leather cover adjacent the hinge line will be retained. In this connection I consider it desirable to have the wire nearest the hinge line spaced a sufficient distance from any metal of the hinge part (see Fig. 2), so as not to impair the desired flexibility of the cover immediately adjacent to the hinge line. As before stated, the particular type of hinge shown is of metal which permits its outer leaf to definitely yield with the cover movement. The book keeps its appearance and wears better when such apparently small points are carefully provided for. By my described construction I retain all the advantages of a desired cover hinge construction and retain transverse cover flexibility while stiffening the cover in a limited zone from top to bottom, to make it resiliently flexible where it is desired to bear the ring pressure, as I will point out.

Each cover 2 and 3 may be constructed as I have described. They are brought together and hinged to the metal parts 15 of the back. The tabs 11 abut and underlie the metal parts extending above and below the metal hinge length (see Fig. 1) and the back of the binder itself is in every way joined to the covers in the usual way for its usual fine and simple appearance, as will be fully understood by those skilled in the art.

In the use of such a binder as I have shown with the new feature incorporated, the advantages are as follows: Whenever the binder rings 1 are pressed against the cover,

as they are by the hand when the book is used (the condition is indicated in Fig. 9 where all rings 1 are shown pressed against the covers), the invisible wires 10 distribute such pressure up and down and particularly along the zone defined by *a*, *b*, *c*, *d*, (see Fig. 3). This zone is generally parallel to the hinge line. The pressure acts to bend the wires. And each of the wires 10 has enough stiffness and resiliency to immediately spread any bending pressure along their length parallel to the hinge line into one or more waves *w*, as in Fig. 9. The wires are all spaced one from another and from the hinge line but connected by flexible parts of the cover material. The pressure is thus spread not only lengthwise but also transversely from one wire to another and to the metal hinge. The latter is constructed to bend and its parts all have a little play for ease of operation, and this helps spread the bending effect. The result of this pressure distribution is that the localized pressure force of the rings against the cover promptly acts over a predetermined area of sufficient extent to obliterate all detrimental effect at any localized point. The action is somewhat like a good bed spring which will always yield under pressure but never take a permanent impression and will, on account of its resiliency, return immediately to its original flat shape.

In flexible cover constructions this yielding action contributes to the desired effect of having flexibility right down to the hinge line. By my wire construction I avoid a compromise cover, such as is stiff from the hinge line outwardly far enough to protect against the ring, and flexible in the rest of the cover. The flexible cover of my construction has all the advantages in appearance of a single ply leather cover and when combined with the stiff binder back it makes the same simple, neat combination that it did before any protecting means against ring pressure was added to the combination. It is a construction of low cost since leather splitting machines are available to prepare the covers economically to receive the wires and the wires are of course quite inexpensive.

I have shown in Fig. 7 a substitute for the wires. It is a flat and very thin piece of spring steel 16 to cover the zone *a*, *b*, *c*, *d* of the cover, and obviously placed in the cover in the same general manner as the wires. When it is used some of the flexibility of the wire construction is lost. But to a considerable extent it has the same advantages. It may be inserted in the cover over the same area as the wires and it is preferable to see that its inner edge is spaced away from the hinge line enough to leave the flexibility adjacent the hinge line. There would be some flexibility any way due to the fact that the spring plate is not actually a part of the metal hinge. But if a space is left between

the two it is much better. The plate will have less tendency to raise an objectionable ridge in the outside surfaces of very thin leather covers or the like of single ply when split for the insertion of the protector plate. The thin metal plate may in some instances be cut longitudinally in parallel slits, leaving an uncut margin all around the plate edge. This will make it more nearly like the wires spaced apart and it will be more flexible.

In the binder construction I have shown, the rings can in no event make any impression on the cover in the space between the metal cover hinge and the inner line of the spring plate. The latter has a width at least sufficient to protect the cover in the critical zone which is about where the rings contact with the cover when the latter is at right angles to the back. And preferably the width of the plate is no more than is necessary for the critical zone. If this is taken into consideration it will be seen that the spring plate need not be very wide. It is preferable to make it as narrow as possible and yet have it perform its function. By so doing the flexibility of the cover is retained to advantage.

In Fig. 8 I have shown a modification in which both a flat, thin piece of spring steel and also wires are used over a larger region in each cover than in the other modifications. In this arrangement the flat piece 16 may be as narrow as in the modification shown in Fig. 7. It is located where the covers bear tangentially against the rings when the binder book is closed in its normal way and gripped by the hand. It is in such condition that the rings are most often pressed through the covers to mar them. The narrow flat piece 16 can take the pressure at this most severe region. And the rest of area beyond the flat piece may be provided with wires 10 to avoid any marking of the cover over the edge of the plate if pressed tightly. In some cases it may not be desirable to provide more than the very narrow flat piece to spread the ring pressure when the binder book is closed and gripped. Then the wires shown in the Fig. 8 modification may be omitted. In such a case it will be seen that the narrow plate is spaced a considerable distance from the hinge line, and is so narrow that the cover flexibility is retained to a remarkable degree. As the cover is bent over sharply on its hinge there will always be a chance for the plate 16 to rock around with the cover. This is important and is provided for by the flexible line between the hinge and metal plate 16.

The particular area *a*, *b*, *c*, *d*, as shown, may of course be varied by the number and spacing of the wires or the area of the flat spring steel piece. In any variation I consider it of particular importance to have some

space or bending line between the hinge line and the metal parts of the pressure spreading means and particularly between any metal hinge parts and said other metal parts.

5 Unless this is done the flexibility of the cover adjacent the hinge line is largely destroyed. And if that is done the cover does not serve its function as particularly desired; it being desirable where flexible covers are used to 10 avoid the feeling in actual use that they have any other predetermined hinge line than the actual one (on each side) immediately adjacent the back.

Having fully disclosed my invention, I 15 claim:

1. In a binder of the ring book type having a back and flexible covers hinged thereto, the combination of covers made up of a single 20 ply for each cover, narrow hinges fastening the covers to opposite edges of the back, each cover having its hinge edge split to form a pocket parallel to the top and bottom surfaces of the cover and to the hinge edge and extending a short distance outwardly from 25 the hinge line, hinge members being fastened on to the adjacent edges or lips of said pockets to hold them tightly together without anything between such lips so as to make the pockets invisible, and parts of thin flexible 30 material made of spring metal extending lengthwise and inside of the pockets and along the covers where the binder rings contact the surface of the pockets whereby any 35 pressure of the rings against the flexible covers will be spread out by the spring metal and the desired thin and smooth appearance of the flexible covers will be retained.

2. In a binder of the ring book type having a back and flexible covers hinged thereto, the combination of covers made up of a single 40 ply for each cover, narrow hinges of thin metal fastening the covers to opposite edges of the back, each cover having its hinge edge split to form a pocket parallel to the top and bottom 45 surfaces of the cover and to the hinge edge and extending a short distance outwardly from the hinge edge, said metal hinges being fastened on to the adjacent edges or lips of said pockets to hold them 50 tightly together without anything between such lips and so as to make the pockets invisible, and long strips of resilient material lying in said pockets and of such small thickness as to avoid bulging said pockets to any 55 substantial extent, said strips being spaced from the hinge lines and lying in those regions of the covers where the binder rings have a tendency to press the covers out of shape.

60 3. In a binder of the ring book type having a back and flexible covers each made up of a single ply hinged to the back, the combination of covers having a series of spring wires laid inside each cover adjacent its hinge line and parallel thereto, said wires being

arranged to receive pressure from the binder rings when the cover is pressed against them and to distribute said pressure.

4. In a binder of the ring book type having a back and flexible covers each made 70 up of a single ply hinged to the back, the combination of covers having integral flaps formed by splitting its material from the inner edge, resilient and thin spring metal parts inserted between said flaps and laminated 75 therewith, narrow metal hinges between the back and covers, the outer parts of the hinges being formed with staples to close the edges of said flaps and bind the covers to the hinge members, said spring metal parts being 80 spaced from the closed edges and lying only in those regions of the cover where the binder rings have a tendency to strike through as the binder is closed.

5. In a binder of the ring book type having a back and flexible covers hinged thereto by metal hinges having staples spaced along the outer edge to fasten the hinge to the cover on both sides of its inner edge, the combination of the metal hinges having staples, and the covers, each having an invisible pocket closed by said staples, and in said pocket lying between the surfaces of the cover a spring metal means spaced from the metal of the hinge plate and spread over the region or zone 90 adjacent any contact of the rings with the cover, said spring means being spread over in such thin form as to retain the desired flexibility of the cover and adapted to return the cover near the hinge line to flat form 95 after severe pressure from the rings against the cover.

6. In a binder of the ring book type having a back and flexible covers hinged thereto, the combination of the back and covers, each cover being formed of thin, flexible material and having an incision made along its inner edge portion parallel to its top and bottom surfaces and resilient material in said incision for laminated arrangement with the cover material, means joining the cover to the binder and closing said incision, the resilient material being spaced away from such joining means.

7. A loose leaf book of the ring binder type including flexible covers of single ply material with incisions along their inner edges extending outwardly a distance about equal to half the diameter of the rings for holding the sheets, thin strips of hard resilient material pocketed by said incisions and invisibly lying in position to spread any pressure from the rings against the flexible covers, narrow hinge strips of thin, flat metal attached along 110 the inner edges of the covers and clamping the incisions closed, said thin strips and hinge parts being independent except as joined by the cover material, the covers presenting an appearance of simple single ply thickness 115 120 125 130

with flat surfaces from the hinge line outwardly.

8. A loose leaf book of the ring binder type including flexible covers of single ply material with incisions along their inner edges, hard, resilient and thin inserts pocketed by the incisions and located to take the pressure of the rings when the book is closed, hinges fastened along the inner edges of the covers with gripping means to hold the incisions closed, said flexible covers with their invisible inserts presenting flexible portions between the hinges and the inserts, and a substantially uniform thickness and uniformly flat surfaces.

9. The method of making a cover for a loose leaf book which consists in splitting a single ply of soft flexible material along its inner edge and so that the inner leaf of the split portion is thinner than the outer leaf, inserting in said split a short distance back of the edge, a narrow thin strip of hard flexible material, closing the split portions tightly together while pressing the said outer leaf on a flat surface and pressing the inner leaf to take the impression of the narrow strip and then attaching a metallic hinge strip which embraces both inner and outer surfaces of the cover along the tightly closed split edge.

In testimony whereof I have affixed my signature.

JOHN SCHADE.
